Patented July 13, 1965

201,634

PUSHBUTTON LOCKING DEVICE

Charles C. Davis and Raymond L. Erickson, Brookfield,
Wis., assignors to Cutler-Hammer, Inc., Milwaukee,
Wis., a corporation of Delaware

Filed Aug. 4, 1964, Ser. No. 81,162

Term of patent 14 years

(Cl. D50—5)

Fig. 5

Fig. 7

Fig. 6

Fig. 8

Fig. 9

FIGURE 1 is an isometric view of a pushbutton locking device incorporating our new design;
FIG. 2 is a front elevational view thereof;
FIG. 3 is an end elevational view thereof;
FIG. 4 is an elevational view of the other end thereof;
FIG. 5 is a top view thereof;

FIG. 6 is a bottom view thereof;

FIG. 7 is a view like FIG. 1, but showing a part thereof in a different position;

FIG. 8 is a view like FIG. 2, but showing the aforementioned part in the same position as in FIG. 7, and

FIG. 9 is a view like FIG. 1, but showing the aforementioned part in the same position as in FIGS. 7 and 8.

The portions shown in broken lines in FIG. 1 are for purposes of illustration only.

We claim:

The ornamental design for a pushbutton locking device, as shown and described.
